(57) **CLAIM**

The ornamental design for an electric fireplace LED decorative light as shown and described.

DESCRIPTION

FIG. 1 is a perspective view of an electric fireplace LED decorative light showing the claimed design;

FIG. 2 is another perspective view thereof;

FIG. 3 is a front elevational view of FIG. 2;

FIG. 4 is a rear elevational view of FIG. 2;

FIG. 5 is a right side view of FIG. 2; and,

FIG. 6 is a top plan view of FIG. 2.

The dash-dash broken lines depict portions of the electric fireplace LED decorative light that form no part of the claimed design. The dash-dot broken lines illustrate environmental structure of the electric fireplace LED decorative light that form no part of the claimed design.
